UNITED STATES PATENT OFFICE.

LUTHER E. MORRISON, OF NEW YORK, N. Y., ASSIGNOR TO MERGENTHALER LINOTYPE COMPANY, A CORPORATION OF NEW YORK.

TYPOGRAPHICAL DISTRIBUTING MACHINE.

Application filed May 29, 1925. Serial No. 33,639.

To all whom it may concern:

Be it known that I, LUTHER E. MORRISON, a citizen of the United States, residing at New York, in the county and State of New York, have invented certain new and useful Improvements in Typographical Distributing Machines, of which the following is a specification.

This invention relates to typographical distributing machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through distributing mechanism to the magazine from which they started.

More particularly, it relates to the distributing mechanism employed in such machines, which mechanism comprises generally one or more distributor bars which effect the release of the matrices at different points for return to their proper magazine channels, a set of rotatable screws for conveying the matrices along the distributor bars until they reach their proper point of release, and a reciprocating finger or similar means operated in synchronism with the screws so as to feed the matrices thereto one at a time at each rotation thereof. For many years, the machines were equipped with quarter-inch pitch conveying screws, but in recent years they have been equipped with screws of the form set forth in the Rogers Patent No. 1,137,024, and which in practice are given a half-inch pitch. The advantages of this latter type of screw are fully set forth in the Rogers patent and need not be repeated here, although it may be stated that the half-inch pitch considerably increases the speed of distribution of the matrices and also serves to keep them separated from each other during their travel along the distributor bars, as well as to prevent interference between them at the time of their release, thus enabling the distributing mechanism to handle matrices

of greater thickness than was theretofore possible.

The present invention is directed to certain improvements whereby the distributing mechanism may be equipped with the old type of quarter-inch pitch screws and still possess the various advantages of the improved half-inch pitch screw above referred to, as well as other advantages which are inherent in the use of screws of the old type. To this end, it is proposed to speed up the screws so that they will rotate twice as fast as usual, say about 600 R. P. M., and to operate the matrix feeding finger at every other rotation of the screws, instead of at each rotation thereof, as before, so as to preserve the usual rate of feed of the matrices. In the embodiment illustrated, this is accomplished by mounting the operating cam for the matrix feeding finger on a separate stub shaft extending parallel to one of the screw spindles, and by connecting the stub shaft and screw spindle by means of a reducing gear-set which will cause the cam to rotate at half the speed of the screws.

According to this arrangement, it will be clear that the matrices, whether thick or thin, will be fed to the screws regularly and uniformly at every other rotation thereof and hence will be engaged by the alternate convolutions of the screws as they are carried along the distributor bars. In this way, the matrices will always be maintained at a half-inch distance apart and this without slowing up their regular rate of feed to the screws; and, moreover, due to the increased speed of rotation of the screws, the matrices will be carried along the distributor bars at twice the speed previously attained in the case of quarter-inch pitch screws. It will now be seen that, by the simple expedient above indicated, the old quarter-inch pitch screws may be adapted to the new conditions without sacrificing any of the important advantages of the improved half-inch pitch screws. Furthermore, in the case of the quarter-inch pitch screws, owing to the slight angularity or more nearly vertical location of the screw threads, they exercise a much better purchase on the projecting ears of the matrices and have less tendency to cause them to vibrate during their travel along the distributor bars, and besides, afford the matrices

greater clearance when they drop from the distributor bars. These and other advantages will be readily understood by those skilled in the art.

5 In the accompanying drawings, the invention has been shown only in preferred form and by way of example and as applied to a distributing mechanism wherein the matrices are fed to the distributor screws by the 10 ordinary matrix lifting finger. However, it may also be adapted to other forms of distributing mechanism, such as that embodied in the commercial Model 9, wherein the matrices are fed by gravity to the distributor 15 screws under the control of reciprocating pawls or escapements. It should be understood, therefore, that the invention is not limited to any specific form or embodiment, except in so far as such limitations are 20 specified in the appended claims.

In the drawings:

Fig. 1 is a rear elevation of a portion of a linotype distributing mechanism embodying the present improvements; and

25 Fig. 2 is a vertical, transverse section, taken on the line 2—2 of Fig. 1.

As usual, the matrices X are transferred in line from the second elevator A into the distributor box C by the shifter slide B, 30 which pushes the line through the box and up against the stop shoulders C¹ formed on the extensions C² of the box rails C³. The stop shoulders C¹ are disposed in the same vertical plane and are arranged to arrest the 35 foremost matrix of the line directly above and in the path of a reciprocating pawl or finger D, which is adapted to lift the matrices, one after another, above the arresting shoulders C¹ and into the range of action of the distributor screws E. These screws are 40 geared together in the usual way and cooperate with the projecting ears X¹ of the matrices to advance them across the rail extensions C² into engagement with the distributor bar C⁴, and thence along the same 45 until they are released above their respective magazine channels. As shown, the lifting finger D is carried at one end of a bell crank 50 lever F pivoted at F¹ to the distributor box C and provided at its other end with a roller F² cooperating with a constantly rotated face cam G against which it is normally held by the pull spring F³.

55 As before stated, the distributor screws E herein employed are of the old quarter-inch pitch type, but according to the present invention, they are rotated at twice the ordinary speed or about 600 R. P. M., which may be done in any well-known way. Moreover, the cam G, instead of being attached 60 directly to one of the screw spindles, as customary, is now fastened to the end of a stub shaft H, mounted in a suitable bearing H¹, and connected to the spindle of the rear screw 65 by means of a reducing gear arrangement

comprising a small gear E² on the screw spindle and a large gear H² on the stub shaft. In the present instance, the speed ratio of the gears is 2:1, so that the lifter cam will be rotated at the ordinary speed 70 of about 300 R. P. M., or at half the rate of rotation of the screws. It is also pointed out (see Fig. 2) that the upper end of the pivoted lever F is offset sufficiently to bring its roller F² in position to cooperate properly 75 with the cam G, so that the latter may actuate the lifting finger D in the customary way.

As a result of the foregoing arrangement, the matrices will be fed to the screws at 80 every other rotation thereof and advanced along the distributor bar by their engagement with alternate convolutions of the screws, which thus maintain them the proper distance apart and prevent interference between them as they are released from the bar. 85

Although the lifter cam is operated at half the rate of speed of the screws, the feed of the matrices to the screws will be carried on at the usual rate of 300 per minute, due 90 to the increased speed of rotation of the screws. This increased speed of rotation of the screws also has the effect of speeding up the travel of the matrices along the distributor bar and thus hastens their distribution 95 to that extent. Of course the speed of rotation of the screws may vary widely without affecting the principle of this invention, but it is preferred to rotate the screws at twice their regular speed, for the 100 reasons just stated. The essence of the invention resides in the operation of the matrix feeding means at a slower rate of speed than that of the screws, and preferably at half the rate, in order that the matrices may be fed 105 to the screws at every other rotation thereof.

It has heretofore been proposed, in adapting the quarter-inch pitch screws to handle thick matrices, to render the lifting finger momentarily inactive each time a thick matrix is fed to the screws, so as to delay the feeding of the following matrix to the screws. In these prior arrangements, the lifting finger is operated at each rotation of the screws, as usual, but it is caused to make 110 an idle stroke after feeding a thick matrix to the screws, being controlled in its action 115 by the matrices themselves. One of the difficulties of such arrangements is that the actual rate of distribution of the matrices is 120 seriously cut down, owing to the irregular feed of the matrices by reason of the idle strokes made by the lifting finger, not to mention the uncertainty in action of the automatic devices which are necessarily required. 125 It can be seen without further discussion that the present arrangement is radically different from these prior constructions.

130 It is pointed out that while the threads of the distributor screw herein shown and

- described are of the quarter-inch pitch variety, it might be found advantageous to vary their pitch and change the rate of reciprocation of the matrix lifting finger accordingly.
- 5 In other words, and as previously mentioned, the decreased angularity of low-pitch screws has certain advantages over those of greater pitch and these advantages might well be amplified by employing screws of 10 even less than a quarter-inch pitch. Of course, in such event, the rotational rate of the screws would have to be increased and the ratio of the gear H^2 and pinion E^2 modified to suit in order to obtain the best 15 results.
- Having thus described my invention, its construction and mode of operation, what I claim and desire to secure by Letters Patent of the United States, is as follows:
- 20 1. In a typographical distributing mechanism, the combination of a set of rotatable matrix conveying screws, means for feeding matrices to the screws, and means for operating the matrix feeding means at such rate 25 of speed as to cause the matrices to be engaged by nonconsecutive convolutions of the screws, for the purpose described.
2. In a typographical distributing mechanism, the combination of a set of rotatable 30 matrix conveying screws, a reciprocating finger for feeding matrices to the screws, and means for operating said finger at a rate of reciprocation less than the rate of rotation of the screws.
- 35 3. In a typographical distributing mechanism, the combination of a set of rotatable matrix conveying screws, a reciprocating finger for feeding matrices to the screws, and means for operating said finger at every 40 other rotation of the screws, so as to cause the matrices to be engaged by the alternate convolutions of the screws as they are carried along thereby.
4. In a typographical distributing mechanism, the combination of a set of rotatable matrix conveying screws, a reciprocating finger operated by one of said screws for feeding matrices thereto, and intermediate gearing for reducing the rate of reciprocation of the finger in relation to the rate of 45 rotation of the distributor screws, for the purpose described.
5. In a typographical distributing mechanism, the combination of a set of rotatable matrix conveying screws, a reciprocating finger for feeding matrices to the screws, a rotatable cam for operating the reciprocating finger, and means for rotating said cam at half the rate of rotation of the conveying 50 screws.
6. In a typographical distributing mechanism, the combination of a set of rotatable matrix conveying screws, a reciprocating finger for feeding matrices to the screws, a rotatable stub shaft arranged parallel to one 55 of the screw spindles and provided with a cam for operating the reciprocating finger, and reducing gearing connecting the stub shaft and screw spindle, whereby the matrix feeding finger will be operated at a speed less 60 than that of the conveying screws for the purpose described.
7. In a typographical distributing mechanism, the combination of a set of rotatable matrix conveying screws, and means for 65 feeding matrices to the screws at every other rotation thereof irrespective of the relative thickness of said matrices.
8. A combination as set forth in claim 1, characterized by the fact that the matrix conveying screws are rotated at twice their standard speed, while the matrix feeding means are operated at their standard speed.

In testimony whereof, I have affixed my signature hereto.

LUTHER E. MORRISON.
